UNITED STATES PATENT OFFICE.

FRANK P. GRODE, OF KANSAS CITY, MISSOURI.

BILLIARD-TABLE CONSTRUCTION.

1,243,161.

Specification of Letters Patent. Patented Oct. 16, 1917.

Application filed June 23, 1916. Serial No. 105,374.

To all whom it may concern:

Be it known that I, FRANK P. GRODE, a citizen of the United States, residing at Kansas City, in the county of Jackson and

5 State of Missouri, have invented certain new and useful Improvements in Billiard-Table Constructions, of which the following is a full and exact specification.

The present invention relates to billiard 10 table improvements, and aims to provide a knock-down construction wherein all the parts are of an interchangeable standard character. A further object is to devise a 15 neat and compact metallic construction of simple design, strong and durable but as light in weight as practicable, and which shall be economical to manufacture.

With these and other objects in view as will appear in the course of the specification, 20 the invention will now be described in detail in connection with the accompanying drawings illustrating one form of embodiment of the same, after which those features and combinations of parts deemed to be 25 novel will be severally set forth and defined in the appended claims.

In said drawings—

Figure 1 is a plan view of a billiard table construction embodying the present improvements;

Fig. 2 is a longitudinal section taken on the line II—II of Fig. 1, with the top of the table represented in dotted lines;

Fig. 3 is a transverse section on the line 35 III—III of Fig. 1, taken on a larger scale;

Fig. 4 is a fragmentary section on the line IV—IV of Fig. 1, also on a larger scale;

Fig. 5 is an enlarged detail section on the line V—V of Fig. 2; and

40 Fig. 6 is an enlarged perspective view of a clamping plate member hereinafter referred to.

Referring to the drawings in detail, the same illustrate a construction in which the 45 parts of the body or bed-supporting frame are stamped out of suitable sheet metal to form duplicate side members 2 and duplicate end members 4, of the usual downwardly tapered contour, and each having at 50 its top margin the horizontal outwardly projecting flange 6 for receiving and supporting the top bed of the table, which latter is merely indicated by the dotted lines 8 in Fig. 2. The ends of both said side and end 55 members are also formed with the inturned flange projections 10 adapted to be secured

together at the corners of the table by means of the bolts 12. At their bottom margins the side and end members are further formed with the horizontal inwardly projecting flanges 14 serving to provide a neat exterior finish to the body as well as a clamping ledge for attaching the leg members hereinafter described.

A bridge construction of duplicate interchangeable parts of channel cross-section is provided for securely and rigidly bracing the body frame from the interior thereof. This construction comprises a continuous diagonal bridge member 16, duplicate diagonal bridge sections 18, and duplicate transverse bridge sections 20. Those bridge elements which extend into the corners of the body frame are formed with flat end portions 22, cut to fit said corners and turned at suitable angles for adapting the same to be clamped to the corresponding flange projections 10 by means of certain of the bolts 12. The outer ends 24 of the transverse bridge sections 20 are welded to the 70 interior faces of the side members 2 (thereby leaving their outer faces smooth), while the inner ends of said transverse sections 20 as well as of the diagonal sections 18 are provided with the plain flat portions 26 75 adapted to be clamped together and to the continuous bridge member 16 by means of the bolts 28, at substantially the center of the space inclosed by the body frame (see Fig. 5).

The leg members for supporting the body frame at its several corners are composed of duplicate and interchangeable parts, each leg member consisting of a hollow upright section 30 of sheet metal and preferably of 85 rectangular cross-section for harmonizing with the lines of the body frame; a cap section 32, and a base or floor-rest section 34, said cap and base sections being formed 95 with the marginal grooves 36 for accommodating the upper and lower ends, respectively, of the upright section 30 (see Fig. 3). These leg sections are all adapted to be clamped together in the relation shown by means of a centrally arranged bolt 38 100 provided with a nut 40 received within a pocket 42 formed in the cap section 32, a similar pocket 44 being provided in the base section 34 for countersinking the head of 105 said bolt. The bolt is of sufficient length 110 for mounting a second nut 46 thereon, so that a single bolt may be utilized both for

clamping the leg sections together and for securing the same to the horizontal flange projections 14 at the corners. This second nut 46 engages a plate 48 provided with the 5 bolt opening 50 for the bolt 38, said plate resting upon the top faces of the flanges 14 and secured thereto, as by bolts 51, within the corresponding corner of the body frame, and being provided further with a dowel 10 projection 52 of sufficient length to engage an opening 54 in the corresponding cap section 32 for holding the leg against any rotative tendency. One corner of the plate 48 is also formed with a depending boss 56 of 15 the same thickness as the flange 14, to engage the cap section and act as a spacing element and thereby hold the plate in proper horizontal position.

It will thus be apparent that a simple, 20 neat and attractive, as well as strong, rigid and durable construction has been devised for fulfilling the objects of the invention. An important feature of the improvements lies in the interchangeability of the various 25 duplicate parts, these being made up to standard patterns and fitting in any of the analogous positions for which they are designed. The construction also enables the exterior thereof to be kept perfectly smooth, 30 and the arrangement of the corner joints provides a strong reinforcement of the frame at these points by virtue of the in-turned flange portions 10 secured together throughout the depth of the body. The 35 structure is made as light as practicable consistent with strength and durability, and the duplicate interchangeable part feature renders the same extremely economical and inexpensive to manufacture.

40 While the foregoing represents what is now deemed to constitute the preferred form of embodiment of the invention, the right is reserved to all such formal changes and modifications as may fairly fall within the 45 scope of the appended claims.

Claims:

1. A billiard table construction comprising, in combination, duplicate side and end body members, two of the diagonally opposite corners of said body members being 50 connected by a continuous diagonal bridge member, and duplicate diagonal bridge sections connecting the remaining body corners with an intermediate point of said bridge 55 member.

2. A billiard table construction comprising, in combination, duplicate side and end body members, two of the diagonally opposite corners of said body members being 60 connected by a continuous diagonal bridge member, duplicate transverse bridge sections connecting said side body members with an intermediate point of said bridge member, and duplicate diagonal bridge sec-

tions connecting said point with the remaining corners of said bridge members. 65

3. A billiard table construction comprising, in combination, a body frame, and interchangeable leg members at the corners of said frame, said leg members being each 70 made up in sections including a cap section having its outer edges projecting and forming an exposed ornamental margin for the top of the leg member along the corner lines of the frame, and provided with means for 75 detachably clamping the margin of the frame at said corners thereof.

4. A billiard table construction comprising, in combination, a body frame having horizontal flange projections at the corners 80 thereof, and interchangeable leg members each made up in sections including a cap section having its outer edges projecting and forming an exposed ornamental margin for the top of the leg member along the 85 corner lines of the frame, and provided with means for detachably clamping said flange projections at said corners of the frame.

5. A billiard table construction comprising, in combination, a body frame having 90 horizontal flange projections at the corners thereof, interchangeable leg members adapted to be clamped to the corners of said frame, each leg member comprising an upright hollow section and a cap section having 95 its outer edges projecting and forming an exposed ornamental margin for the top of the leg member and provided with a marginal channel for seating the upper edge of the leg member, and means for clamping 100 said leg sections together with said cap section in clamping engagement with said flange projections.

6. A billiard table construction comprising, in combination, a body frame, interchangeable leg members at the corners of said frame, said leg members each comprising an upright hollow section, a cap section and base section, the outer edges of said cap section projecting and forming exposed ornamental margins for the tops of said leg members, said cap and base sections being provided with marginal channels for seating the upper and lower edges, respectively, 110 of said upright sections, and means for 115 clamping said leg sections together with said cap sections detachably engaged with the margin of said frame at the corners thereof.

7. A billiard table construction comprising, in combination, a body frame having 120 horizontal flange projections at the corners thereof, interchangeable leg members adapted to be clamped to the corners of said frame, each leg member comprising an upright hollow section, an exposed ornamental cap section and a base section, a bolt and nut for clamping said leg sections together, 125

and a plate member resting on said flange projections at each of said corners, each of said bolts being also provided with a nut for clamping the plate and cap section of the 5 corresponding leg member in engagement with said flange projections.

8. A billiard table construction comprising, in combination, a body frame having horizontal flange projections at the corners 10 thereof, duplicate interchangeable leg members adapted to be clamped to the corners of said frame, said leg members being made up of duplicate interchangeable sections and each leg member comprising an upright 15 hollow section, a cap section and a base section, a plate member resting on said flange projections at each of said corners and formed with a spacing boss of the thickness of said projections for engagement with the 20 adjoining leg member, and means for clamping said leg sections together with the cap

section and corresponding plate member in clamping engagement with said flange projections.

9. A billiard table construction comprising, in combination, a body frame having horizontal flange projections at the corners thereof, duplicate interchangeable leg members adapted to be clamped to the corners of said frame, each of said leg members comprising an upright hollow section, a cap section and a base section, a plate member resting on said flange projections at each of said corners and provided with a dowel 25 for detachable engagement with the cap section of the adjoining leg member, and means 30 for clamping together the leg sections of each leg member with its cap section and corresponding plate member in clamping 35 engagement with said flange projections. 40

In testimony whereof I affix my signature.

FRANK P. GRODE.
